UNITED STATES PATENT OFFICE.

HIRAM R. SIMPSON, OF SAN FRANCISCO, CALIFORNIA.

DEPRESSIBLE PLATFORM.

Application filed January 19, 1922. Serial No. 530,420.

To all whom it may concern:

Be it known that I, HIRAM R. SIMPSON, a citizen of the United States, and a resident of San Francisco, county of San Francisco, 5 and State of California, have invented a new and useful Depressible Platform, of which the following is a specification.

The present invention relates to improvements in depressible platforms and its particular object is to provide convenient means for raising and lowering a section of a floor relative to the surrounding area. Such depressible platforms are used for various purposes, especially in connection with bank 10 vaults, and a particular advantage of my device is that it can be handled without the application of much force, and that it has suitable spring means associated therewith which automatically assist in the raising 15 20 of the platform, while this spring means is rendered inactive during the time the platform is in its lowermost position.

With these and other objects in view I have illustrated the preferred form of my 25 invention in the accompanying drawing, in which Figure 1 illustrates a vertical cross section through my device along line 1—1 of Figure 2; Figure 2 a top plan view of the same, the cover of the platform being removed, and Figure 3 a sectional detail view 30 of a spring arrangement adapted to aid in the raising of the platform. While I have shown only the preferred form of my invention, it should be understood that various 35 changes or modifications may be made within the scope of the claims hereto attached without departing from the spirit of the invention.

Referring to the drawing in detail, it will 40 be seen that a pit (1) is provided in the floor (2), which is assumed to be of concrete, and that a movable platform (3) consisting of a metal cover (4) resting on a plurality of transverse angle bars (6) is supported 45 over the pit on links (7) and (8) forming toggle joints. Two pairs of these toggle joints are provided, one joint for each corner of the platform. The lower ends of the lower links (7) are pivotally supported on 50 pins (11) secured in any desired manner in the walls of the pit so that each two of them forming a pair are axially aligned. The upper ends of the upper links (8) are pivot- 55 ed to the transverse rods (12) disposed in parallel relation to the pins (11) and supporting the two ends of the platform. The

free ends of the links (7) and (8) are pivot- 60 ed to each other by means of pins (13), by means of which the links are actuated.

Considering the first pair of links, that is 65 the ones on the left hand side in the drawing, it will be seen that normally the lower link (7) is in a vertical position, while the upper link (8) slants somewhat to the right. The pin (13) has a third link (14) attached thereto, the free end (16) of which can be actuated by a lever (17) pivoting on a stud (18). It will be seen that when the lever (17) is pulled to the left the link (14) will 70 actuate the pin (13) to revolve around the pin (11) so as to turn the link (7) into the position indicated in dotted lines, the pin (13) at the same time carrying the link (8) with it so that the left hand portion of the platform is lowered. 75

The motion of the left hand pin (13) is transmitted to the right hand pin (13) by means of a lever (19) pivotally supported on the transverse shaft (21). It will be noted that on the right hand side the link 80 (8) of the toggle joints slants toward the left. The two pins (13) are connected to the ends of the arms (22) and (23) of the lever (19) by means of connecting members (24) and (26), and it will be readily seen that if 85 the links (7) of the left hand side revolve to the right, the motion of its pin (13) will be transmitted to the pin (13) on the right hand side through the lever (19) and the connecting members (24) and (26), but in 90 such a manner that the right hand side pin (13) revolves to the left as indicated in dotted lines, thereby lowering the right hand side of the platform simultaneously 95 with the left hand side.

To facilitate the raising of the platform, which of course is brought about by manip- 100 105 110 115 ulating the lever (17) in the opposite direction, I provide the device (27) comprising a cylinder (28) through the closed end (29) of which extends a rod (31) provided with a spring (32) confined between the plunger (33) at the end of the rod and the closed end (29) of the cylinder. The cylinder itself is pivotally secured as shown at (34) to a bracket (36), while the end of the rod (31) is pivoted to a rounded body portion (41) of the lever (19) in such a manner that when the lever (19) is turned a bend (42) in the rod (31) will allow its end pivot (43) to pass around the shaft (21) so as to pass its center. When in this position the spring

(32) is rendered inactive due to the fact that the shaft (21) lies within its line of draft, but when the lever (19) has been turned slightly in an effort to raise the platform, the spring will become active and automatically perform a part of the work.

The operation of the device will be readily understood. When it is desired to lower the platform the lever (17) is pushed toward the left, as indicated in dotted lines, which will cause the two links (7) to turn on the transverse rods (12), while the links (8) follow this motion so as to lower the platform. During this operation the end of the 15 rod (31) of the spring arrangement will be carried around the shaft (21) so as to set the spring. While in this position the spring although under tension is not effective because the shaft (21) lies within its line of 20 action. When the lever (17) is pushed to the right the links (7) will revolve on their respective rods in the opposite direction causing the lever (19) to turn, and as soon as the end (43) of the rod (31) has passed 25 around the shaft (21) the spring (32) will become operative and assist in raising the platform.

An adjustable stop is provided in operative proximity to each pin (13) and consists 30 of a screw (20) the head of which limits the motion of the link (7) so that the height of the platform in its uppermost position can be adjusted.

I claim:

35 1. A depressible platform having two co-acting toggle joints supporting the same, means for actuating one of the toggle joints and means for transmitting the motion of the first joint to the second, whereby the

platform is lowered or raised, said last means 40 comprising a lever pivotally mounted between the two joints and pivotal connecting links between the knuckles of the joints and the arms of the levers, and having spring means associated therewith for aiding in 45 raising the platform.

2. A depressible platform having two co-acting toggle joints supporting the same, means for actuating one of the toggle joints and means for transmitting the motion of 50 the first joint to the second whereby the platform is lowered or raised, said last means comprising a lever pivotally mounted between the two joints and pivotal connecting links between the knuckles of the joints and 55 the arms of the levers, having spring means associated therewith for aiding in raising the platform, and means for rendering the spring inactive when the platform is in one of its end positions.

3. A depressible platform having two co-acting toggle joints supporting the same, means for actuating one of the toggle joints and means for transmitting the motion of the first joint to the second, comprising a 65 lever pivotally mounted between the joints, operative connections between the arms of the lever and the knuckles of the joints whereby the platform may be lowered and raised, and a spring actuated connection 70 between one side of the lever and a stationary point for aiding in raising the platform, a bend being provided in said connection allowing its far end to travel around the fulcrum of the lever so as to render the spring 75 inactive while the platform is in its lowermost position.

HIRAM R. SIMPSON.
